PULL CHAIN AUTOMATIC LOCK SLIDER

Louis H. Morin, Bronx, N. Y., assignor of one-half to Davis Marinsky, Bronx, N. Y.

Application September 12, 1942, Serial No. 458,071

10 Claims. (Cl. 24—205.5)

This invention relates to sliders for separable fasteners employing stringers coupled and uncoupled by a slider movable along the stringers. More particularly, the invention relates to an automatic lock slider of this class employing a tiltable lock element or pin actuating element with which a chain or other flexible member is coupled in forming a pull for operating the slider along fastener stringers whereby operation of the slider by the pull will release the lock element. The novel features of the invention will be best understood from the following description when taken together with the accompanying drawing, in which certain embodiments of the invention are disclosed, and in which the separate parts are designated by suitable reference characters in each of the views; and in which:

Fig. 1 is a perspective view of a slider made according to my invention.

Fig. 2 is a section on the line 2—2 of Fig. 1 on an enlarged scale.

Fig. 3 is a view similar to Fig. 2, showing only a part of the construction and with parts in a different position.

Fig. 4 is a transverse sectional view through a slider showing a modification; and,

Fig. 5 is a sectional view similar to Fig. 1, showing only a part of the construction and showing another modification.

In lock sliders of the kind under consideration it has been customary to employ substantially rigid strip or tab-like finger pieces or pulls for actuating or releasing the lock element of the slider. It is the purpose of my present invention to so construct the lock element or the means directly actuating said element as to adapt the same for the use of flexible pulls, such for example, as pull chains, straps, and the like.

In the accompanying drawing I have illustrated certain adaptations of the invention and in Figs. 1 to 3 inclusive, 10 represents a more or less conventional slider body having top and bottom walls 11 and 12 joined and spaced at one end by a connecting web 13, said walls being flanged as seen at 14, note Fig. 1, to form the channel or channels of the slider body.

In the present construction I provide centrally of the top wall 11, preferably adjacent the web end 13 of the slider, a socket 15, in which is freely disposed a lock element 16.

The lock element 16 comprises a ferrule 17 with which is loosely coupled a headed pin 18. The outer end of the ferrule 17 has a large socket 19 to receive one ball end 20 of a pull chain 21. At the base of the socket 19 is a contracted por-

tion 22 which forms a seat for the headed pin, and below this contracted portion is an outwardly flared opening 23 which provides free angular movement of the pin with respect to the ferrule 17, as will be seen on comparing Figs. 2 and 3 of the drawing. The ferrule 17 also has an enlarged annular flange 24 at the base thereof which forms a seat for a spring 25, the other end of the spring seating upon an inturned flange 26 at the open end of the socket 15.

When the socket opening is formed initially, the walls thereof will not include the flange 26. After the parts are assembled in the socket, this flange is formed by turning the upper end of the ring-like body 27 inwardly.

Centrally of the bottom wall of the socket 15 is a conical aperture 28 which opens into the channel of the slider body 10, so that in the normal position of the lock element 16, as seen in Fig. 2, the pin portion 18 of said element will be projected into the channel. However, when the pull 21 is engaged for operating the slider, the ferrule portion 17 will be tilted as indicated in Fig. 3 of the drawing and the pin part 18 withdrawn from the channel of the slider body. This operation will be performed regardless of the direction in which the ferrule is tilted. The moment the pull 21 is released, the spring 25 will automatically return the pin part 18 to operative position.

In Fig. 4 of the drawing is shown a cross section through a slider taken through a cup shaped socket portion 29 similar to the portion 27. In this construction, a ferrule 30 is provided which differs from the ferrule 17, in that two pins 31 and 32 are coupled to opposed sides thereof with the heads of the pins engaging recesses in the flange of the ferrule as seen at 33. A chain 34, similar to the chain 21, is coupled with the ferrule and a spring 35 normally supports the ferrule with the pins 31, 32 in operative position, that is to say, projected into the channel of the slider. In Fig. 4 a section is shown through two stringer tapes 36 and 37, simply to indicate the pins 31, 32 engaging links of the stringers 36, 37 respectively. While the section in Fig. 4 would indicate the pins 31 and 32 in direct opposed relationship to each other, it will be apparent that these pins may be staggered or offset sufficiently to engage the links of both stringers and to compensate for the spacing between the links of opposed stringers.

In Fig. 5 of the drawing is shown another modification in which the slider 38 has, on one wall thereof, a ring-like projection 39 within which is

a large aperture or socket 40 opening into the channel of the slider through a smaller aperture 41. This structure forms a cup shaped socket in the slider somewhat of the type shown in Figs. 1 to 3 inclusive, and instead of employing the in-turned flange 26, the socket 40 has an annular groove 42 near the outer end thereof, in which may be fitted a spring ring or washer 43, or this washer may be in the form of a solid ring and seated in an enlargement at the outer end of the socket and retained therein by turning the flange portion 44 inwardly as with the construction disclosed in Figs. 1 to 3.

In the socket is arranged a lock element 45, which comprises a pin-like structure having a lower conical or pointed end 46 adapted to project into the channel of the slider and an upper apertured end 47 with which a link chain or other flexible pull 48 may be coupled. This coupling may, for example, be made through the use of a split ring 49. Intermediate the ends of the element 45 is an enlarged flange portion 50 which fits within the socket 40 and forms a seat for a spring 51, the other end of the spring seating on the washer or ring 43.

With the construction shown in Fig. 5 of the drawing, operation of the slider through the medium of the pull or chain 48 will cause the lock element 45 to be raised or tilted in the socket 40 against the action of the spring 51 to withdraw the pin 46 from the slider channel, and on the release of the pull, the spring will automatically return the lock element to operative position.

With the construction shown in Fig. 5, the lock element comprises a unitary body, that is to say, the pin portion 46 is integral with the parts 47 and 50, but it will be apparent that the element may be composed of independently movable parts as is taught in the other figures, and in the same sense the structure of said other figures may be integral. In some instances, relative movement of the pin part with respect to its support is desirable. In other instances this independent movement can be dispensed with. It will also be understood that the shape and structure of the lock pin element may be such as to provide a more or less positive lock of the slider on the stringers, whereas in other instances this element may be so constructed as to provide release of the lock element when the stringers are subjected to excessive strains tending to separate the same. This last operation will be performed by forcible outward movement of the lock element against its supporting spring by the link or links engaging the element.

It will be understood that, with the present construction, the lock element and pull comprises a unit which as an assemblage is insertable into the slider socket. In some instances the unit is permanently retained in position by in-turned flanges, but by using spring ring retainers, as at 43, this unit may be made detachable for any purpose. In connection with this latter feature, when dealing with plastic type of pulls, different color combination in the balls or links of the chain may be provided by simply substituting a new unit. Thus these units, as such, would constitute articles of manufacture which may be supplied to the merchant for interchanging or substitutions as mentioned above. It will also appear that such changes may be made for repair or other purposes and any means may be provided to facilitate quick attachment and detachment of these combined pull and lock units.

Upon consideration of the present structure it

will also appear that the flexible pull, such for example, as the chain, may be said to include an integral lock element. In other words, operation of the lock element, to move the same into inoperative positions, is controlled by the pull chain, means being employed to support the element in operative position.

Having fully described my invention, what I claim as new and desire to secure by Letters Patent is:

1. The combination with a channelled slider body for separable fastener stringers, of a lock element movably supported in one wall of the slider body and retained against displacement from said wall, a spring normally supporting the lock element in operative position, a chain movably coupled with said element, forming a pull for actuating the slider body and movement of the lock element into inoperative position, said element including a ferrule portion, and said chain having a ball end universally coupled in said ferrule portion.

2. The combination with a channelled slider body for separable fastener stringers, of a lock element movably supported in one wall of the slider body and retained against displacement from said wall, a spring normally supporting the lock element in operative position, a chain movably coupled with said element, forming a pull for actuating the slider body and movement of the lock element into inoperative position, said element including a ferrule portion, said chain having a ball end universally coupled in said ferrule portion, and said element including a pin part movably supported in the ferrule portion.

3. In lock sliders for separable fastener stringers, a slider body comprising spaced walls joined at one end by a connecting web, said walls defining a channel extending through said body, one wall of said body having an outwardly projecting ring forming in said wall a large socket, the wall of the slider defining the base of said socket having an aperture opening into the socket and the channel of said slider, a lock element adapted to be arranged in the socket of said body, and said ring having means retaining said element against displacement from said socket.

4. The combination with a channelled slider body, of a universally tiltable member, a flexible pull coupled with said member for tilting the same, a lock part centrally of said member extending into the channel of said slider, and a spring normally supporting said member with said part in operative position.

5. In lock sliders for separable fastener stringers, a channelled slider body having spaced walls, a housing on one of said walls, said housing having side walls, an open top portion and a bottom having an opening communicating with a channel, a lock element tiltably mounted within said housing and defining with the side walls thereof a space providing clearance for said tilting, resilient means in said space resiliently urging said lock element toward said channel, means retaining said resilient means in said space, a pin carried by said lock element and extending through said opening in the slider wall and normally engaging a fastener element, and a pull adapted to tilt said lock element against the bias of said resilient means to release the pin from said engagement.

6. In lock sliders for separable fastener stringers, a channelled slider body having spaced walls, a housing on one of said walls, said housing hav-

ing side walls, an open top portion and a bottom having an opening communicating with a channel, a lock element mounted for universal tilting within said housing and defining with the side walls thereof a space providing clearance for said tilting, resilient means in said space resiliently urging said lock element toward said channel, means retaining said resilient means in said space, a pin carried by said lock element and extending through said opening in the slider wall and normally engaging a fastener element, and a pull adapted to tilt said lock element against the bias of said resilient means to release the pin from said engagement.

7. In lock sliders for separable fastener stringers, a channeled slider body having spaced walls, one of said slider walls having an outwardly projecting boss and an opening, said boss having a socket therewithin partly defined by interior side walls, said socket being open at the top and having a base communicating with a channel through said opening, a lock element supported at the base of said socket, resilient means engaging said lock element and interior side walls of said socket and adapted to maintain said element tiltably mounted in said socket, and pin means extending from said lock element through said opening and adapted to engage and disengage a fastener element in consonance with the tilting of said lock element.

8. In a slider for separable fastener stringers of the type as herein described, having a channeled slider body including spaced walls, one of which has an opening therein for the passage of a pin, the improved locking structure which comprises a pin-carrying lock element having a base portion, side walls and a top portion, said element being tiltably supported on said slider wall with the pin extending from the base of the lock element through said opening, pull means connected to said lock element at the top

thereof and adapted to tilt said element on its base, an open top housing on said slider wall and surrounding said lock element, and resilient means engaging said housing and side walls of the lock element to resiliently resist the tilting of said lock element.

9. In a slider for separable fastener stringers of the type as herein described, having a channeled slider body including spaced walls, one of which has an opening therein for the passage of a pin, the improved locking structure which comprises a pin-carrying lock element having a base portion and a top portion, said element being tiltably supported on said slider wall with the pin extending from the base of the lock element through said opening, pull means connected to said lock element at the top thereof and adapted to universally tilt said lock element on its base, and means resiliently engaging said lock element intermediate the top and base thereof and resiliently resisting the tilting thereof.

10. In a slider for separable fastener stringers of the type as herein described, having a channeled slider body including spaced walls, one of which has an opening therein for the passage of a pin, the improved locking structure which comprises a pin-carrying lock element having a base portion and a top portion, said element being tiltably supported on said slider wall with the pin extending from the base of the lock element through said opening, pull means connected to said lock element at the top thereof and adapted to universally tilt said lock element on its base, means resiliently engaging said lock element intermediate the top and base thereof and resiliently resisting the tilting thereof, said means comprising an annular boss on the slider wall and surrounding said lock element and in spaced relation thereto, and a spring confined between said lock element and boss.

LOUIS H. MORIN.
